UNITED STATES PATENT OFFICE.

ISRAEL C. SMITH AND EDWARD E. HERRINTON, OF GRAND RAPIDS,
MICHIGAN.

FOLDING BED.

SPECIFICATION forming part of Letters Patent No. 380,223, dated March 27, 1888.

Application filed May 2, 1887. Serial No. 236,877. (No model.)

To all whom it may concern:

Be it known that we, ISRAEL C. SMITH and EDWARD E. HERRINTON, citizens of the United States, residing at Grand Rapids, in the county 5 of Kent and State of Michigan, have invented a new and useful Folding Bed, of which the following is a specification.

Our invention relates to improvements in that class of folding beds in which the frame 10 supporting the bed is adapted to turn into a vertical position upon pivots located near one end of said frame, to which end are attached counterbalance-weights.

The objects of our invention are, first, to 15 provide a simpler and less expensive structure; second, to provide a folding bed adapted to be readily taken apart for removal and shipment; third, to provide an improved movement of the various parts; fourth, to provide means of 20 adjusting the counterbalancing-weight to determine the backward tendency of the bed when in a vertical position. We attain these objects by the mechanism illustrated in the accompanying drawings, in which—

25 Figure 1 is a plan view of a bed embodying our invention; Fig. 2, a vertical section of the same on the line $x-x$ of Fig. 1, showing the bed open; Fig. 3, the same closed, and Fig. 4 a detail showing one corner of the frame in perspective.

Like letters refer to like parts in all the figures.

The frame which supports the bed consists of the rails A A, boxes D and E, and the foot-board C, attached to each other as follows: The 35 rails A are provided with longitudinal strips a and transverse strips b, which engage with corresponding grooves in the ends of the boxes D and E. Said rails are also provided with strips 40 l l, between which are inserted the ends of the foot-board C, which is provided with blocks g, which engage with notches in the strips l and prevent vertical movement of said foot-board.

To prevent the box E from moving upon the 45 strip a, said box abuts against a strip, a', and has a strip, e, attached, which engages with the corner of the box D. Each of the corners of the bed-frame is secured by a hook, d, attached to the rail A and engaging with an eye in the 50 foot-board C or box D. The slat c, to prevent spreading of the side rails, has a dovetail notch,

o, at its respective ends, which engages with the beveled ends of the blocks n', and to prevent said slat from falling out of place when the bed is raised to a vertical position the 55 side toward the foot-board is beveled, as shown at m, the beveled end of the block n overhanging the same and holding said slat down.

F F are side frames, which are pivoted to the rails A at f' by means of a suitable bolt. Sufficient bearing-surfaces are provided between 60 said frames and rails to keep them at all times in the same plane without necessity for attaching said frames to each other.

B is the head-board, which is hinged at the 65 bottom to the box D and supported in a vertical position by arms G G, pivoted to the said head-board at f''' and to the side frame, F, at f'', the hinges f and the pivots f' f'' f''' being located approximately at the several angles of 70 a parallelogram.

I is a board extending across the lower edge of the foot-board and parallel to the same, to which it is attached by hinges h. Said board has attached at either end the legs k, and at 75 the middle may also be attached any suitable ornament, i. Its lower edge may also be cut into any suitable ornate form, so that the whole, when in the position shown in Fig. 3, 80 will form a suitable cornice or finish at the top of the bed, and when in the position shown in Fig. 2 will support the foot of the bed and form a suitable finish for the same.

The bottom of the frame may be closed by suitable drapery or by panels or a mirror, or 85 both, as most convenient.

The boxes D and E are made tight and strong enough to hold sand or other suitable material to counterbalance the moving parts.

The operation of our device is as follows: By 90 detaching the hooks d, the pivots f' f'', and hinges f the various parts are readily separated and can be packed in small space for transportation or removal from place to place. When set up for use, sand or other convenient 95 material can be used in the boxes, thus saving the expense and transportation of the usual cast-iron weights. By using two boxes, D and E, the sand can be so apportioned between them that the bed will exactly balance when 100 in a vertical position or have only a slight backward tendency. The quantity of sand

can also be exactly adjusted to balance the bed when complete. In closing the bed as the foot rises the head-board descends through the arc of one-fourth of a circle, remaining at all times 5 in a vertical position. As the rails A attain a perpendicular position, their upper edge comes in contact with the head-board and further movement is arrested. The board I and parts attached, being hinged to the foot-board 10 above their center of gravity, tend to retain their vertical position and automatically assume the positions shown in Figs. 2 and 3 when the bed is opened and closed.

We are aware that a box attached to a folding 15 bed and adapted to contain counterbalance-weights, a head-board having a vertical movement in grooves in the side frame and hinged to a frame carrying the bed, said frame having pivots adapted to move horizontally to accommodate the vertical movement of said head-board, side frames pivoted to the movable frame of a bed and sustained in a vertical position by attachment to each other, and folding beds adapted to be taken apart are not new. 20 We do not claim any or all of these, broadly. 25

What we claim and wish to secure is as follows:

1. In a folding bed, the combination of the rails A, having strips a, a', and b, boxes D and 30 E, having grooves engaging with the strips a and b, and a strip, e, and hooks connecting said rails and boxes, substantially as described.

2. In a folding bed, the combination of the rails A, having strips a, a', b, and l l, boxes 35 D and E, having grooves engaging with strips

a and b and a strip, e, a foot-board, C, having blocks g, and hooks d, substantially as described.

3. In a folding bed, the combination, with the supporting frames, of a swinging frame 40 pivoted thereto and having at one side of the pivot of the swinging frame a compartment for a gravitating weight, and a weight in said compartment composed of a finely-divided material in bulk less than the capacity of the 45 compartment, whereby said weight may change position relative to the pivot to determine the backward tendency of the bed when upright.

4. In a folding bed, the combination, with 50 the supporting side frames and the swinging bed-frame pivoted thereto, of a head-board hinged to the swinging frame and rigid arms G, pivoted to the head-board, extending directly to the supporting frames and pivoted to the 55 latter, substantially as described.

5. In a folding bed, the combination, with the supporting side frames, of a swinging frame pivoted thereto and having two compartments differently situated with respect to 60 the pivot of the swinging frame, and weights composed of loose sand in said compartments adapted to automatically shift as the bed is raised or lowered, substantially as set forth.

ISRAEL C. SMITH.
EDWARD E. HERRINTON.
